(57) **CLAIM**

The ornamental design for a display stand, as shown and described.

DESCRIPTION

FIG. 1 is a front perspective view of a display stand, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the folded state diagram of its front face thereof;

FIG. 10 is a front perspective view of another embodiment thereof;

FIG. 11 is a rear perspective view of another embodiment thereof;

FIG. 12 is a front view of another embodiment thereof;

FIG. 13 is a rear view of another embodiment thereof;

FIG. 14 is a left side view of another embodiment thereof;

FIG. 15 is a right side view of another embodiment thereof;

FIG. 16 is a top view of another embodiment thereof;

FIG. 17 is a bottom view of another embodiment thereof;

FIG. 18 is the folded state diagram of another embodiment's front face thereof;

FIG. 19 is an enlarged detail view of area 19 in FIG. 1 thereof; and,

FIG. 20 is an enlarged detail view of area 20 in FIG. 10.

The broken lines in the drawings illustrate the portions of the display stand, which form no part of the claimed design. The dash-dot-dash broken lines encircling the enlarged views are for annotative purposes only and form no part of the claim thereof.

1 Claim, 20 Drawing Sheets
